DESIGN FOR AN ENSEMBLE DRESS

Jack Kirschner, New York, N. Y.

Application April 12, 1935, Serial No. 56,348

Term of patent 3½ years

To all whom it may concern:

Be it known that I, Jack Kirschner, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

Figure 1 is a front view of an ensemble dress showing my new design.

Figure 2 is a rear view of the ensemble dress shown in Figure 1.

Figure 3 is a front view of the dress unit of the ensemble dress shown in Figure 1.

Figure 4 is a rear view of the dress unit of the ensemble dress shown in Figure 3.

The dominant feature of my design resides in the embroidery on the collar of the dress portion of the ensemble, and on the sleeves of the jacket portion of the ensemble, and which embroidery consists of rows of contrastingly colored cross stitches, alternating with rows of contrastingly colored circles.

I claim:

The ornamental design for an ensemble dress, substantially as shown and described.

JACK KIRSCHNER.
